TWO-WAY ELECTRICAL COMMUNICATION
SYSTEMChauncey L. Calkins, Chicago, Ill., assignor to
Lothar A. Ederer, Chicago, Ill.

Application March 16, 1934, Serial No. 715,904

3 Claims. (Cl. 177—338)

My invention relates to improvements in means and apparatus for two-way electric communication, and in one form to semi-automatic two-way message transmitting equipment, and may especially be adapted for communicating systems, such as are required in factory production control.

One object of my invention is to provide an apparatus capable of transmitting relative complex messages in a semi-automatic manner. Another object of my invention is to provide apparatus that may be operated by persons entirely unskilled in the use of telegraphic apparatus. Another object of my invention is to provide a simple apparatus for such intercommunication as is required in factory control of interdepartmental service, by which an almost unlimited variety of simple messages may be rapidly exchanged.

For the purpose of illustrating my invention, I have shown a complete workable apparatus including various structural details, and I have also shown a schematic wiring diagram of such complete two-way intercommunicating circuit.

It will be understood that these parts may take other forms than those shown and that the circuit arrangement may be in other forms than that shown, and still accomplish the same purpose in the same manner. Hence, the showing here made is to be considered as in a sense diagrammatic.

Fig. 1 is a front elevation of a two-position central switchboard and recorder units;

Fig. 2 is a section along the line 2—2 of Fig. 1;

Fig. 3 is a perspective view of the metallic framework construction of such a board;

Fig. 4 is a detail of a recorder unit bank, with parts omitted, used in the board shown in Fig. 1;

Fig. 5 is a vertical section along the line 5—5 of Fig. 4, illustrating the reset magnet for an individual indicator used in the recorder unit bank;

Fig. 6 is an enlarged section along the line 6—6 of Fig. 4, illustrating the set-up mechanism of such indicator;

Fig. 7 is another sectional view of such indicator, taken along the line 7—7 of Fig. 9;

Fig. 8 is a section along the line 8—8 of Fig. 7, showing the method of attachment of such indicator unit to the frame;

Fig. 9 is a section along the line 9—9 of Fig. 4;

Fig. 10 is an enlarged section along the line 10—10 of Fig. 4, illustrating the step-up switch and the method of connecting electrical circuits;

Fig. 11 is a sectional view through line 11—11 of Fig. 10;

Fig. 12 is a sectional view along the line 12—12 of Fig. 9;

Fig. 13 is an enlarged section of the step-up switch along the line 13—13 of Fig. 11;

Fig. 14 is a schematic wiring diagram of the circuit;

Fig. 15 is an across-the-line diagram of the circuits comprising the system.

Like characters indicate like parts throughout the specification and drawings. For the sake of clarity, in describing the electrical circuit and system, designation has been chosen in which sub-assemblies are given capital letters, and elements in each sub-assembly small letters of corresponding character with appropriate superscripts, and the wiring designated by figures.

Referring to Fig. 1, A is a casing or cabinet carrying a plurality of slotted visual indicator 20 housings B. C and C¹ are automatic impulse generating dials, and C², C², C² are a group of transfer or reset switches associated with dial C. C³, C³, C³ are a group of transfer or reset switches associated with dial C¹. C⁴ is a main power 25 switch. C⁵ is a lock type buzzer switch. D, D, D are three jack plugs carried on flexible cables and associated with dial C¹. D¹, D¹, D¹ are another set of three jack plugs, carried on flexible cables and associated with dial C. E, E¹ and 30 E², and also E⁵, E⁶, are groups of signal lamp lenses.

Referring to Fig. 2, D, D, D are jack plugs attached to flexible cables d, d, d. C¹ is an indicating dial. A indicates a housing or cabinet. 35 a and a¹ indicate vertical metallic cabinet supporting members. a², a² indicate horizontal metallic cabinet supporting members. a³, a³ indicate metallic cross bracing. a⁴, a⁴ indicate horizontal metallic shelf members, which together with 40 members a⁵ and a⁶ forms a front shelf or horizontal apron. a⁷, a⁷ are angularly disposed metallic supports adapted to carry relatively heavy 45 groups of recorder-unit banks B¹. a⁸, a⁹, a¹⁰ are metallic framework members of the extended vertical portion of the members carrying other relatively heavy assemblies. a²⁰ is a line terminal group for attachment of interior electric wiring and its connection with external electrical 50 circuits and wiring.

Referring to Fig. 3, in addition to members already described in Fig. 2, here shown in perspective, the following cross members appear; a¹¹ a shelf cross bar, a¹² upper bank cross bar, and a¹³, a¹³ horizontal, panel cross members, 55

also special bracing member a^{14} , attached only to the central shelf supporting member a^4 . The cross bar a^{12} and the adjacent bank cross bar a^{13} may be connected by vertical members a^{15} .

- 5 Referring to Fig. 4, B is a recorder unit bank adapted to carry 12 indicator units G. These indicators are mounted and positioned in slotted bar b^{14} and upon the slotted positioning bar b^{15} , which are secured to the end plates b^{16} to form 10 cradles adapted as a whole to be mounted upon the supports a^7 . Electrical connections are made from the indicator units G to a series of insulated plugs b^{17} , each carrying three terminal sockets b^{18} , b^{19} and b^{20} . To provide for certain 15 common wiring, an insulated plug b^{21} is provided carrying two small sockets b^{22} , b^{23} . b^{24} is a reset magnet. b^{25} is a supervisory lamp receptacle and bracket. F is a step-up switch unit, which sub-assembly is generally similar to indicator units and is similarly mounted along with the indicator units in the general bank frame B.

Referring to Fig. 5, g is a signal lamp associated with each recorder unit bank and in phantom is shown in corresponding sight glass or opal E⁵. b^{24} is the reset magnet which actuates the reset rod b^{30} and associated fingers b^{31} . The magnet b^{24} is by means of its frame g^3 mounted together with the signal lamp upon one of the end plates b^{16} . g^4 is an indicator unit frame plate upon which is mounted a shaft g^5 carrying an indicator drum shown in Fig. 4 as g^6 . Upon this shaft is mounted a ratchet wheel g^7 actuated by the pawl g^8 . The pawl is carried upon a compound lever comprising the member g^9 pivotally attached to member g^{10} . Member g^9 is rounded for rolling contact at the end opposite the pawl carrying end. Its rounded face is adapted to engage a fulcrum plate g^{30} projecting from the plate g^4 . The ratchet is held against 40 return motion by stop g^{11} , which stop is pressed against the ratchet by means of the spring g^{12} . Spring g^{13} normally holds the pawl g^8 into engaging position with the ratchet wheel and at the same time retains the rounded end of the 45 lever g^9 in engagement with the fulcrum plate g^{30} . The compound lever is mounted on a shaft g^{14} which in turn is driven by its operating magnet g^{15} .

Referring to Fig. 7, g^6 is an indicator drum attached to the step-up mechanism of the indicator unit. Upon this drum is a cam g^{16} adapted to engage insulated button g^{17} upon the spring switch leaf g^{18} . g^{19} is a pair of electrical switch contacts carried upon spring leaves g^{18} and g^{20} .

55 Referring now to Fig. 8, the end plate b^{16} and the slotted support bar b^{15} are clearly shown. The ratchet and pawl mechanism together with the operating magnet appear clearly in side view, g^{15} being the magnet, g^{10} the armature, and 60 main lever upon which is pivoted the rolling contact lever g^9 carrying the pawl g^8 which acts upon the ratchet wheel g^7 .

Referring to Fig. 9, a spring member g^{31} is a return spring rigidly attached at one end to the plate g^{32} mounted upon the fixed shaft g^5 and at the other to the rotatable drum g^6 , which spring resists stepping up motion of the drum by the pawl mechanism and which returns the drum to normal position when the stop g^{11} is released.

70 Referring to Figs. 10, 11 and 13, F is an advance unit or step-up switch carried upon a frame plate f, operated by a magnet f^1 having an armature f^2 and acting upon a compound lever similar in all respects to that of the indicator unit. f^3 is a switch contact housing cover.

f^4 is the insulated switch contact block carrying a series of switch contacts f^5 , f^6 . f^6 is a common contact wiper ring having an electric connection attached thereto leading to the switch terminals. The switch contact block is rigidly 5 mounted upon the stud or pin f^7 . Upon this stud or pin is the step-up mechanism f^8 of a form generally used. It is a spring returnable by means of the spiral spring f^9 . This step-up mechanism carries upon its end the flexible 10 spring wiper f^{10} which contacts the switch buttons f^8 and the flexible wiper f^{11} , which wipes the ring contact f^6 .

Referring to Fig. 12, the detailed construction of the drum with its mounting, drive and return 15 means are clearly shown. g^6 is the character bearing drum, g^7 the ratchet wheel attached to the drum but free to rotate on the stud g^5 . g^{32} is the return spring plate and g^{31} the spring.

Referring to Fig. 14, H, H¹ are impulse generating units similar to the automatic dial of the dial telephone. They contain impulse generating cams h , impulse switch points h^1 , special impulse generator h^2 , and the off normal switch h^3 operated by the special arm h^4 . J and J¹ are two indicator banks comprising the individual indicator units j , j^1 , j^2 , j^3 , j^4 and j^5 in the bank J, and j^6 , j^7 , j^8 , j^9 , j^{10} and j^{11} etc. in the bank J¹. K and K¹ are step-up switch units associated with the indicator banks J, J¹. The step-up 30 switch units contain switches carrying the arms k^6 , k^7 , which pass over the series of contacts k^8 , k^9 , k^{10} , k^{11} , k^{12} and k^{13} , in unit K, and k^{14} , k^{15} , k^{16} , k^{17} , k^{18} , and k^{19} in unit K¹. L and L¹ are reset magnetic trips for the indicator banks 35 and the step-up switch units of each group. M and M¹ are bell signals associated with each group. m , m^1 and m^2 are signal lamps associated with each group. N is a battery supplying power to the system. O is a transfer or reset switch 40 located at the central station carrying the contact points o^1 , o^2 , o^3 , and o^4 . P is one of a series of jack plugs at the central station, having three individual contacts p , p^1 and p^2 . Q is one of a series of line jacks at the central station Q¹ indicating a second such line jack connected to another sub-station not shown. The line jack Q has the individual contact leaves or points q , q^1 , q^2 , q^3 and q^4 . R is a reset button at a sub-station. It has the contact points r . S is a call 50 button located at a sub-station. It has the contact points s . T is a call relay having the magnet t , and the contact points t^1 , t^2 . U is a return call relay having the compound winding u , u^1 , and the contact points u^2 and u^3 . V is a 55 spark suppressing condenser bank. v^1 , v^2 are a spark suppressing condenser and resistance. v^3 , v^4 and v^5 are a spark suppressing assembly including condensers and resistance. The wiring connecting the various parts of the apparatus 60 will be fully described in the discussion of the use and operation of the invention.

The use and operation of my invention are as follows:

A central station is provided which may accommodate any desired number of operators, the number depending in turn upon the number of sub-stations, which each operator is able to handle in normal traffic. In the particular form shown, a single board is shown which may accommodate two operators, or may, in certain cases, be operated by one person. This board is capable of receiving messages from a plurality of sub-station dispatchers. Since the handling of messages is identical in all cases for all sub-station 75

dispatchers, the schematic wiring diagram shows merely the central station and one-sub-station dispatcher, with a line jack indicating one or more additional sub-station dispatchers and the central station. The sub-station dispatchers may be disposed, for example, throughout a factory, one placed near each machine, and the central station may be located in the superintendent's office. A workman, then, may wish to transmit the information that his machine has stopped for one reason or another, that he requires a certain part, or that he requires certain service or that a certain job is finished. To place such a call, he depresses the call button S upon his sub-station dispatcher. Wire 1 is the main negative lead and wire 2 the main positive lead. Negative connection is made to the call button S from the negative side of the battery N through the main negative power lead 1. Positive connection exists from the positive side of the battery N through the wire 2 through the signal lamp m^2 , and further through wire 2 through the cable X, to the winding u of the tandem wound relay U, from this relay to and through the wire 3 to the relay T, and through wire 4 from the relay T to the contact s of the call button S. Closure of this switch then will cause lamp m^2 to glow and this lamp being located upon the switchboard of the central station will indicate to the central station operator that a certain sub-station is calling. The establishment of the circuit energizes the relay T, closing the contacts t^1 and t^2 . The closure of contact t^1 places that side of the relay T in negative connection and holds this relay energized. This contact also will then hold the relay U locked in position with contacts u^2 closed and contacts u^3 open. The closure of contact t^2 makes negative connection through the wire 5 to one side of the signal lamp m and also to one side of the buzzer M, which may be cut out by the switch M^2 . The other sides are connected to the positive side of the battery N by the positive power wire 9, hence the signal lamp m and the audible signal M register, calling the operator's attention to the fact that a signal is being sent. The central station operator, having been signalled, places the plug P in its appropriate line jack Q to answer the call. The independent electrical connections are thereby made, the contact point p of the plug is in engagement with the contact member q^1 , the contact member p^1 engages the member q^2 and the contact p^2 of the plug P is in engagement with the member q ; further the contact members q^3 and q^4 are closed indirectly. This causes the supervisory lamp m^1 of the sub-station to glow, indicating that the operator of the central switchboard is now ready for a message. Electrical connections are made from the battery N, through positive wire 2, contact members q^4 , q^3 , line 15, wire 13 to the supervisory lamp m^1 , thence through the line 14 and negative line 1 back to the battery. Another electrical circuit is established from the battery N, positive wire 2, contact members q^4 , q^3 , line 15, through the winding u^1 of the tandem relay U, the contact points u^2 , and wire 1 back to the negative pole of the battery. This electrical circuit locks the tandem wound relay U which had been energized by the winding u previously described. However, it will be realized that as soon as the central switchboard operator inserts the plug P into the line jack Q the relay U will be energized by means of the winding u^1 , regardless of whether the winding u is energized hereafter or not. The pur-

pose of energizing and locking the tandem wound relay is to keep the contact switch u^3 separated which consequently prevents sounding of the buzzer or signal device M¹ which is shunted across the line 15 and negative line 1 by the wires 26 5 and interposed switch u^3 .

The workman may now dial his message, and in so doing as soon as the dial H¹ is moved off the normal position, the arms h^4 and h^2 are moved away from their respective switch points, 10 allowing the switch points h^3 to close and to remain so until the dial returns to its normal position, as illustrated in Figure 14. Closing of the switch points h^3 establishes an electrical circuit through the electro-magnet k of the step-up 15 unit K and the electro-magnet k^1 of the advance unit K¹ which by means of the ratchet wheels k^2 , k^3 and associated actuating means instantly rotate the commutator switch arms k^6 and k^7 clockwise, referring to the position in which they 20 are shown in Figure 14. The switch arm k^6 then rests upon the contact k^8 and the switch arm k^7 of the step-up unit K¹ then rests upon the contact k^4 . The electrical circuits for the step-up units are from the battery N through the positive wire 2, contact points q^4 , q^3 of the line jack Q, wire 15, wire 13 and wire 12, switch points h^3 , line 18 to the step-up unit magnet k^1 of the sub-station dispatcher, which is connected to the negative wire 1 leading to the negative pole of 30 the battery. Likewise the shunt wire 10 is in electrical connection with the switch member h^3 , delivering electrical current through the contact member q^2 of the line jack Q, contact member p^1 of the plug P, wire 19 to the electro-magnet k 35 of the step-up unit K which is connected to the negative wire 1 completing the circuit to the negative pole of the battery. A spark suppressing condenser bank is placed upon one side of this circuit for the purpose of suppressing sparks at 40 the impulsive contacts. The electrical connections established by the wiper arms k^6 , k^7 of the step-up units K, K¹ then places the indicator units j and j^6 in operating connection through the wires 20 and 21, the far side of the operating 45 magnets being connected to main negative lead 1. Then, as impulse generator H¹ is manipulated by means of the cam h, impulses generated will be sent as the result of the movements of the contact leaves h^1 through the wire 17, the contact k^4 of the step-up unit K¹ and the wire 20 to the indicator j^6 , and also through the wire 30, the line jack q and contact p^2 and wire 31 to the arm k^6 of the step-up unit K, and thence through wire 21 into the indicator j. Consequently, both these indicators will simultaneously receive a series of impulses dependent upon the manipulation of the dial of the impulser. These indicators will then be stepped up so that their drum faces will show character corresponding to 50 the character dialed or determined by the manipulation of the impulser H¹. This, then, shows to both the transmitting and receiving operators simultaneously the first character of the message which may be any simple number or letter of a 55 group of 5, 10, 15, depending upon the construction of the impulser and its dial. Upon return of the dial of the impulser H¹ to neutral position, the contact h^3 is opened. This de-energizes the magnets k and k^1 of the respective step-up 60 switch units, preparing these units for a further step-up. Upon the next motion of the dial of the impulser H¹, this contact h^3 will close and will transmit another impulse to these step-up 65 switch units, as in the previous case. This sec- 70 75

ond impulse will cause a second step-up of the respective units simultaneously, placing the arms upon the second contacts k^9 and k^{15} of the step-up units, and consequently bringing indicators j^1 and j^7 into operating position. These indicators then respond to impulses sent out by the second manipulation of the dial and impulser H^1 , registering simultaneously for both transmitter and receiver the second character of the message, which may also be in one of a designated group of simple characters. This procedure is continued until the message is complete, which may extend, in the case of the drawings shown, to 6 characters. It is, of course, obvious that a greater number of indicators, and consequently a greater number of characters, may be used, and that a greater number of character positions may be provided permitting longer messages. In other words, the system is not to be construed as being confined to any specific number of characters or character positions.

It will be noted that in the central station, upon the functioning of any indicator, the contact j^{12} associated with it will close, and that upon closing, this completes a circuit from the positive side of the battery through wire 9 through the supervisory lamp m^3 , thence through the contact j^{12} and into the main negative lead 1. This supervisory lamp indicates that one or more indicators are off normal. There are a similar set of contacts associated with the indicators upon the sub-station dispatcher which do not, however, perform a like function. These contacts make negative connection from main negative lead 1 through contact j^{13} of any particular indicator and the wires 22 and 3 to the call relay T, cutting this relay out, causing its contacts to open, thus disconnecting buzzer M upon the central switchboard and the lamp m . The closing of any contact j^{13} , establishing negative connection through the wire 22, will, however, keep relay U energized through the winding u since there is a positive connection from the other side of this winding through wire 2. This relay remaining closed, the lamp m^2 indicating to the central station operator the station calling, remains lighted. The indicator units upon both systems may be cleared after the central station operator has received the message satisfactorily by throwing a key switch O. In the construction shown in the drawings, this key switch is thrown to the left, which is a non-locking position. This operation closes the contact members o^1 , o^2 and makes negative contact directly to the reset magnet L through the wires 23 and 24, and also through the continuation of wire 24 to the contacts p and q^1 , thence into wire 11 to the reset magnet L^1 which receives positive current through the wires 13, 15, switch contacts q^3 , q^4 and positive wire 2 from the battery N.

Should the workman desire to clear the indicators upon both the transmitter and receiver, as for example, in the case of error made, he depresses the reset button R, which has an action similar to the throwing of the switch O in that negative connection is made from main negative lead 1, through contact r to wire 25 and thence to wire 11, which is connected to one side of the reset magnet L^1 , and through contacts q^1 and p of the plug P and wires 24 and 23 in similar position with respect to the magnet L. These magnets having then negative connection upon one side, are energized since positive connection is made through wires 13 and 15, the contacts q^3 , q^4 and the main positive power wire 2. Should

the central station operator wish to signal the sub-station operator, the operator merely inserts the plug P into the appropriate line jack Q. This closes the contacts q^3 , q^4 and makes positive connection through to wire 15 through wire 26 with the interposed contact u^3 , to the buzzer M^1 , which sounds. Upon the sounding of the buzzer the workman responds by depressing the call button S in the same manner as though he were signalling the central station operator. The pressing of the call button S makes connections already described and puts the apparatus into position for transmission. Central station operator has a dial H similar in all respects to the dial H^1 . To operate this dial as a sender, the operator throws the switch O into a locking position which in the showing of Fig. 14, is to the right. This places the contacts h^1 of the impulser into communication with the element p^2 of the plug through the contacts o^4 of the switch and also places the contacts h^3 of the impulser into communication with the element p^1 of the plug. These two elements complete the circuit as already described, which permits impulses to be transmitted simultaneously to both banks of indicators.

I claim:

1. In a message transmitting system, a calling station including means for sending a message, a receiving station including means for indicating a message received, means operatively connecting the calling station and the receiving station, and the respective message sending means and the message indicating means, whereby messages sent from the calling station are received and indicated at the receiving station, message indicating means at the calling station, said message indicating mechanism at the calling station including a part movable in response to the dispatch of a message, a signal at the receiving station, means for energizing the signal from the calling station, and means responsive to movement of said movable part of the message indicator at the calling station for deenergizing said signal.

2. In a message transmitting system, a calling station including means for sending a message, and indicating means for indicating a message sent, a receiving station including means for indicating the receipt of a message from the calling station, means operatively connecting the message sending mechanism and the message indicating mechanism of the respective stations for the transmission and receipt of messages; a signal located at the receiving station, a circuit for energizing said signal, means for energizing said circuit from the calling station, said message indicating means at the calling station including a part movable in response to the dispatch of a message from the calling station, said signal energizing circuit including switch means located at the calling station, and means operable in response to movement of said movable part of the indicating mechanism for opening said switch to deenergize the signal upon receipt of a message from the calling station.

3. In a message transmitting system, a calling station including means for sending a message and means for indicating a message sent, a receiving station including means for indicating a message received, means operatively connecting the calling station and the receiving station and the respective message sending means and the message indicating means whereby messages dispatched from the calling station are received at

the receiving station and indicated at both stations, said message indicating means including parts movable in response to the dispatch of a message, signal means at the receiving station including a message to be sent signal and a message received signal, means for energizing the message to be sent signal from the calling sta-

tion, and means operable in response to movement of the indicating mechanisms at the calling and receiving stations in response to the dispatch of a message for respectively de-energizing the message to be sent signal and energizing the message received signal.

CHAUNCEY L. CALKINS.
